UNITED STATES PATENT OFFICE.

THOMAS E. MURRAY, JR., AND JOSEPH B. MURRAY, OF BROOKLYN, NEW YORK.

METHOD OF ELECTRICAL WELDING.

1,339,971.

Specification of Letters Patent. Patented May 11, 1920.

Application filed January 3, 1920. Serial No. 349,185.

To all whom it may concern:

Be it known that we, THOMAS E. MURRAY, Jr., and JOSEPH B. MURRAY, citizens of the United States, residing at Brooklyn, in 5 the county of Kings and State of New York, have invented a certain new and useful Improvement in Methods of Electrical Welding, of which the following is a specification.

10 As a result of many experiments in electrically welding the registering edges of two hollow objects of sheet metal, we found that said edges, while the current was acting, became more or less out of registry, thus 15 changing the contact area at the joint, modifying the heating effect of the current and affecting the perfection of the weld. For some time the cause of this continued obscure, but finally we discovered that the 20 walls of the objects were evidently set into transverse vibration by the alternating current, and so the source of the trouble having been recognized, the problem reduced itself to finding a way to eliminate the difficulty. 25 This we have now accomplished by the method hereinafter set forth.

When the hollow object—as, for example, the longitudinal half section of a tube—is seated directly in an electrode in which it 30 closely fits, that portion of its total vibration amplitude which acts outwardly from the rest position of the half section wall is stopped by the contacting wall of the electrode. But the portion of said vibration 35 amplitude which acts inwardly is unchecked, so that the contacting walls of the work, being free to move in this direction become relatively displaced, as before, at their abutting edges. After trying many expedients 40 to overcome this, we found the simplest conception the most effective and satisfactory solution of the problem.

In the accompanying drawing—

Figure 1 is an end view of the longitudinal half section of a cylindrical tube seated in 45 an electrode. Fig. 2 is a similar view, the half section being rectangular in shape.

Similar letters of reference indicate like parts.

50 In Fig. 1, A is an end view of a semi-tubular object seated and fitting in the elec-

trode B. If nothing more is done, the outward vibrations of the wall of the object will, as we have said, be stopped by the contacting electrode, but the inward vibrations 55 in the direction of the arrows 1, Fig. 1, will be unchecked. But all that is necessary to stop them is to make the object sufficiently resilient as that when it is placed in the electrode, it will be compressed and so 60 exercise an outward pressure on said electrode. To illustrate: the semi-tubular object may be made, as shown at C, in dotted lines, Fig. 1, of a diameter greater than that of the seat in the electrode, so that to introduce it into said seat it must be compressed and to the diameter of object A. Any tendency then of its wall to move inwardly is opposed by its own outwardly acting resiliency. The extent of inward movement, if unchecked, being easily recognized, 65 for any given example of a class or series of identical objects it is a simple proceeding to give them a dimension sufficient to cause them to exert a counter-balancing or over- 70 balancing force. That done, the edges at the weld remain in registry while the current is on.

We claim:

The method of preventing transverse vibration of the edges of a hollow object of sheet metal during the electrical welding of said edges to the registering edges of a similar object by means of an alternating current, which consists in forming said object with a transverse dimension greater than the corresponding transverse dimension 80 of a recess formed in an electrode, seating said object in said recess, and thereby compressing said object to cause the same to 85 press resiliently against its seat in said electrode; whereby tendency of said object to inward vibration is met by its own outwardly acting resiliency.

In testimony whereof we have affixed our 95 signatures in presence of two witnesses.

THOMAS E. MURRAY, JR.
JOSEPH B. MURRAY.
